Patented Oct. 31, 1916.

UNITED STATES PATENT OFFICE.

BERNARD DENNIS, OF MALDEN, MASSACHUSETTS, ASSIGNOR OF ONE-HALF TO SAMUEL O'LANSKY, OF BOSTON, MASSACHUSETTS.

DEVICE FOR SHARPENING TAILORS' CRAYONS.

1,202,975.

Specification of Letters Patent. Patented Oct. 31, 1916.

Application filed January 25, 1916. Serial No. 74,117.

To all whom it may concern:

Be it known that I, BERNARD DENNIS, a subject of the Czar of Russia, residing at Malden, in the county of Middlesex and 5 State of Massachusetts, have invented new and useful Improvements in Devices for Sharpening Tailors' Crayons, of which the following is a specification.

The object of the present invention is to 10 provide a device for sharpening tailors' crayons. Crayons used by tailors for marking cloth must be provided with sharp edges substantially like the edge of a chisel.

My present invention provides two holders, one of which holds the crayon and the other of which holds a plurality of knives arranged to shave the crayon. The knives are arranged in two series, and those of each 20 series are arranged in stepped relation so that each knife will remove a comparatively thin chip or shaving. The aggregate stock removed by all the knives is such that a single stroke of the movable element will be sufficient to sharpen the edge of the crayon, 25 and the fact that the knives are arranged so that no one of them will remove a chip or shaving of excessive thickness avoids breaking off the corners of the crayon as the knives leave the latter.

30 Of the accompanying drawings, which illustrate one form in which the invention may be embodied: Figure 1 represents a side elevation, a portion of the operating rod or handle being broken out. Fig. 2 represents 35 a vertical section through the device as shown by Fig. 1. Fig. 3 represents a horizontal section through the device, showing the knife holder in plan view. Fig. 4 represents an end elevation of the right-hand end 40 of the device. Fig. 5 represents a vertical cross section through the structure intersected by line 5—5 of Fig. 2. Fig. 6 represents a vertical cross section, on a larger scale, through the knife holder as indicated 45 by line 6—6 of Fig. 2. Fig. 7 represents a side elevation of a tailor's crayon whose lower edge has been partly sharpened by the device. Fig. 8 represents an inverted plan view of the lower edge of the crayon partly 50 sharpened as shown by Fig. 7, showing the successive degrees of sharpening as performed by the successive knives.

The same reference characters indicate the same parts wherever they occur.

55 The holder 10 for the crayon 11 is a cylind-

ric casing, in the present instance, and is provided with a slot 12 in its upper side into which the lower edge of the crayon is inserted for sharpening. The holder 10 is provided with base members 13 adapted to 60 rest upon a flat horizontal support and capable of receiving screws (not shown) for fastening it to such support. The ends of the holder 10 are closed by plates 14, 15, but the lower portion of the plate 14 is cut away to 65 admit a substantially semi-cylindric receptacle 35 for the chips or shavings.

The knife holder comprises a rod 16 having a handle 17 here shown in the form of a knob. One of the holders is movable 70 relatively to the other to afford sharpening movement, and in the present instance the knife holder 16 is the movable element. It is movable longitudinally, and its movement is guided by a tube 18 affixed at its 75 ends to the plates 14 and 15. Two strips, 19 and 20, of thin sheet steel are affixed to and carried by the rod 16, and the rod is slotted for their reception, as shown by Figs. 5 and 6. The lower portions of the 80 said strips are arranged in the rod and are affixed to the latter by fasteners such as screws 21. The guide tube 18 has a slot 18' at its upper side to afford traverse of the 85 plates 19 and 20 as the rod 16 is reciprocated. In the present instance the knives are formed on the strips 19 and 20, and for this purpose the latter are cut away to form openings x' , x^2 , x^3 , and x^4 (Fig. 2). Such openings provide the strip 19 with edges 90 a' , a^2 , a^3 and a^4 , and provide the strip 20 with similar edges indicated respectively at b' , b^2 , b^3 and b^4 , which edges are sharpened to cut or shave the crayon. As shown by Fig. 6, the edges of each series are arranged 95 in stepped relation, each edge, excepting the foremost, being arranged to cut deeper than the one ahead of it. In consequence of this arrangement the edges a' and b' will act first and will remove a relatively thin chip or shaving, while the edges a^2 and b^2 will cut slightly deeper and remove another thin chip or shaving, and so on, the edges a^4 and b^4 converging to a meeting point, as clearly 100 shown by Fig. 6, to trim the crayon to a sharp edge.

As shown by Fig. 3, the plates 19 and 20 converge from the cutting edges a' , b' toward the right-hand end of the device. This converging relation sets the successive 110

cutting edges in the desired stepped relation. The fact that the cutting edges are formed on the plates 19 and 20 keeps them in the desired relation to each other, even when 5 they are undergoing a sharpening operation. They may be readily sharpened by means of a thin flat stone, the openings x' , x^2 , x^3 and x^4 affording access to the edges for the purpose of sharpening them. This form of 10 structure avoids the necessity of readjusting the edges after each sharpening operation.

The effect of the several cutting edges on the crayon is illustrated by Figs. 7 and 8, the cuts made by edges a' , b' being indicated 15 at c' , d' , those made by edges a^2 , b^2 being indicated at c^2 , d^2 , those made by edges a^3 , b^3 being indicated at c^3 , d^3 , and the sharp edge made by edges a^4 , b^4 being indicated at e . The thickness of stock removed by each 20 knife edge is so thin that the likelihood of breaking off the corner of the crayon as the knife edge leaves the latter is avoided. Such breaking of the crayon has been an objectionable result of sharpening devices hitherto made, for the reason that they have cut 25 too deeply and have required so much cutting stress as to result in breakage. The strips 19 and 20 are extended in advance of the foremost edges a' , b' and the upper portions 30 21, 22 of such advance portions are arranged to form a trough (Fig. 5) to receive the crayon. The portions 21 and 22 meet at 23 to form the bottom of the trough, and the meeting point of edges a^4 and b^4 35 (Fig. 6) is in alignment with the bottom of such trough. The crayon is thus prevented from being inserted so deeply as to enable the foremost cutting edges a' , b' to break off the corner of the crayon as they leave the 40 latter.

Referring to Figs. 1, 2 and 3, the knife holder is retracted to the right as far as it will go, the right-hand ends of the strips 19 and 20 abutting against the right-hand end 45 of the casing. When the knife holder is in this position the trough-forming portions 21 and 22 are in register with the crayon-receiving opening 12 of the casing 10, and the device is ready to receive a crayon. Assuming now that a crayon is inserted into 50 the opening 12 and it is desired to sharpen the crayon, a single stroke of the knife holder from right to left is sufficient to perform the sharpening operation. As the 55 knife holder moves to the left, the cutting edges a' , b' are the first to engage the crayon. An abutment 24 is affixed to the interior of the tube 10 in position to engage the left-hand vertical edge of the crayon, 60 and to sustain the cutting stress. The abutment 24 is slightly narrower than the trough formed by the portions 21 and 22, so that said portions may pass the abutment on opposite sides of the latter. As the knife 65 holder advances, edges a' , b' remove a thin

chip or shaving and form the cuts c' , d' indicated in Fig. 8. In due course the cutting edges a' , b' reach the crayon and remove other thin chips or shavings and form the cuts indicated at c^2 , d^2 . The other cutting 70 edges reach the crayon successively, and each one in turn removes a thin chip or shaving. The range of movement of the knife holder is sufficient to carry the rear cutting edges a^4 , b^4 beyond the left-hand edge of the crayon, 75 so that the lower edge of the crayon is reduced to a sharp edge, as indicated at e (Fig. 8), throughout its length with one stroke of the knife holder; but notwithstanding the fact that the aggregate removal 80 of crayon is sufficient to produce a sharp edge in one stroke, the breaking of the lower left-hand corner of the crayon is avoided, because no one cutting edge cuts deep enough to produce breakage. As the cutting 85 edges traverse the crayon, the chips or shavings are discharged through the openings x' , x^2 , x^3 and x^4 and dropped into the receptacle 35. The receptacle may be withdrawn at any time from the left-hand end 90 of the tube 10 to dispose of the accumulation of chips or shavings.

The knife holder may be withdrawn from the right-hand end of the tube 10 and entirely detached, so that the cutting edges 95 may be sharpened from time to time. For the purpose of permitting such detachment, the right-hand end plate 15 is provided with an opening 25. A gate 26 is provided for preventing unintentional withdrawal of the 100 knife holder. This gate is in the form of a curved bar and is arranged against the inner face of the end plate 15. A knob 27 having a screw-shank 28 extends through a curved slot 29 in the end plate 15 and has screw-threaded engagement with the gate 26. By screwing the knob tightly against the plate 15 the gate 26 may be clamped in operative position, as shown by Figs. 2, 3, 4 and 5. In order to remove the gate from the path of 110 the knife holder it is only necessary to unscrew sufficiently to relieve the clamping pressure and to slide the knob to the lower end of the slot 29.

I claim:

1. A device for sharpening tailors' crayon, comprising a knife holder and a crayon holder, one of which is movable relatively to the other to afford crayon-sharpening movement, means for guiding the movable holder relatively to the other, a pair of blades affixed to said knife holder and arranged to form a V-shaped trough to receive an edge of the crayon, each of said blades having a series of openings and each such opening having a sharp edge arranged to shave the crayon, said edges being arranged in stepped relation so that each one behind the first will remove the stock trimmed by the one ahead of it. 115 120 125 130 135 140 145 150 155 160 165 170 175 180

2. A device for sharpening tailors' crayon, comprising a casing, a tube therein, said tube having a slot extending longitudinally thereof, a rod arranged in said tube and adapted to slide lengthwise thereof, and a pair of blades affixed to said rod in confronting relation to each other and arranged to traverse said slot of said tube, said blades forming a V-shaped trough for

the crayon, each of said blades having an opening and a sharpening edge thereat for shaving the crayon, said casing having a crayon-receiving opening arranged to register with said trough.

In testimony whereof I have affixed my signature.

BERNARD DENNIS.
